CLAIM

The ornamental design for an electric concrete transportation cart, as shown.

DESCRIPTION

FIG. 1 is a left, frontal isometric view showing the best mode known at this time of my new electric concrete transportation cart;

FIG. 2 is a right, frontal isometric view thereof;

FIG. 3 is a left, rear isometric view thereof;

FIG. 4 is a right, rear isometric view thereof;

FIG. 5 is a left side elevational view thereof;

FIG. 6 is a right side elevational view thereof;

FIG. 7 is a front view thereof;

FIG. 8 is a rear view thereof; and,

FIG. 9 is a top plan view thereof.

1 Claim, 9 Drawing Sheets
